UNITED STATES PATENT OFFICE.

RICHARD DALTON, OF WILMETTE, ILLINOIS.

EXCAVATING-MACHINE.

No. 868,912.

Specification of Letters Patent.

Patented Oct. 22, 1907.

Application filed June 8, 1907. Serial No. 377,973.

To all whom it may concern:

Be it known that I, RICHARD DALTON, a citizen of the United States, and a resident of Wilmette, in the county of Cook and State of Illinois, have invented 5 certain new and useful Improvements in Excavating Machines; and I do hereby declare that the following is a full, clear, and exact description thereof, reference being had to the accompanying drawings, and to the letters of reference marked thereon, which form a part 10 of this specification.

This invention relates to improvements in excavating or ditching machines, and the invention consists in the matters hereinafter set forth and more particularly pointed out in the appended claims.

15 My improvements are herein shown as applied to a ditching machine of the same general type as that set forth in my prior U. S. Letters Patent No. 677,538, dated July 2nd, 1901, but certain of the improvements may be applied to other types of wheel ditching ma- 20 chines.

As shown in the drawings:—Figure 1 is a side elevation of an excavating machine made in accordance with my invention. Fig. 2 is a top plan view thereof. Fig. 3 is an enlarged side elevation of the scoop carrying 25 wheel, showing the scoops and excavating plows and cutters carried thereby. Fig. 3^a is a rear elevation of the machine with parts omitted, showing the excavation in cross-section. Fig. 4 is a vertical section taken on line 4—4 of Fig. 1, looking forwardly. Figs. 5 and 6 30 are detail sections taken on lines 5—5 and 6—6, respectively, of Fig. 4. Fig. 7 is a detail view illustrating a portion of the driving connections for rotating the scoop bearing wheel. Figs. 8 and 9 are vertical sections, taken on lines 8—8 and 9—9, respectively, of Fig. 2. 35 Fig. 10 is a detail of one of the scoops, its supporting arm and the devices for limiting the lateral swing of said arm. Fig. 11 is a detail illustrating one of the latches for locking the scoop bearing arms to the rim of the wheel. Fig. 12 illustrates said parts in a changed 40 position. Fig. 13 is a section taken on line 13—13 of Fig. 11. Fig. 14 is a section taken on line 14—14 of Fig. 12. Fig. 15 is a perspective view of the latch shown in Figs. 11 and 12. Fig. 16 is a detail illustrating devices 45 for locking certain of the plow bearing arms to the wheel rim, constructed to swing said arm away from the wheel. Fig. 17 is a section taken on line 17—17 of Fig. 16. Fig. 18 is a detail illustrating the manner of operating one of the side cutters carried by the wheel. Fig. 19 is a detail as seen from line 19—19 of Fig. 18. Fig. 20 is a 50 cross-section taken on line 20—20 of Fig. 18.

As shown in the drawings, 25 designates a generally horizontal frame of open work construction adapted to be moved along the path of the proposed excavation on supporting wheels 26, 26 at the front end and 27, 27 55 at the rear end thereof. The front wheels are mounted on an axle 28 having central pivotal connection with the

frame and constitute steering wheels, and the rear wheels are mounted on an axle 29 fixed in the rear end of the frame. The steering wheels are controlled from a steering shaft 30 connected through the medium of the usual worm gear mechanism 31, a horizontal transverse shaft 32 and chains 35 with the ends of said front axle, said parts operating in a familiar manner to turn the steering axle on its pivot. In accordance with one of the features of construction, the machine is motor 60 driven, the motor shown consisting of a steam engine 34 of any suitable type carried on said frame and supplied with steam from a generator 35. Pivotaly connected with the rear end of said frame is a wheel supporting and adjusting frame consisting of two rearwardly extending wheel supporting arms 40, 40 and upwardly directed beams 41, 41 which are rigidly secured at their lower ends to the rearwardly extending wheel supporting arms, and converge toward their upper ends and attached together at the longitudinal center of the machine frame. The frame thus composed is pivotally mounted on the rear end of the main frame in such manner that the rear ends of the wheel supporting arms may be raised and lowered to raise and lower the wheel carried thereby, for the purpose of adjustment, for the purpose of loosening obstructions which the scoops may meet or permit the scoops to be cleared of such obstructions, and for the purpose of raising the wheel entirely above the ground when the machine is to be moved from place to place, as will 80 75 85 90 95 100 105 hereinafter appear. The pivotal connection of the wheel supporting frame comprises the rear stationary axle 29. A supplemental frame 42 is supported on said beams 41 of the wheel supporting frame and the rear axle 29 in a manner to be capable of vertical movement relatively to said parts on which it is supported. Said supplemental frame comprises two separate parallel, vertical beams 43, 43 connected at their upper ends by a transverse beam 44. The connection between the beams 41 and said beams 43 comprises a cross arm 45 attached in any suitable manner to the upper ends of the beams 41 and provided at its ends with grooved fittings 46 with which its beams 43 have vertically sliding engagement. A similar connection is made at the lower ends of said beams 43 with fittings 47 carried by the rear axle 29. Said fittings 47 have the form of collars and said collars are fixed from movement endwise of the axle between other collars 47^a which are fastened to the axle by set screws 48. The purpose of the supplemental frame will be fully explained hereinafter.

Mounted on the rear ends of the arms 40 of the wheel supporting frame is a rotative wheel designated as a whole by 50. Said wheel carries a plurality of scoops or buckets 51. It is driven by the engine 34 through the medium of driving mechanism, hereinafter to be described, including a sprocket chain or belt 52 trained about the rim 53 of the wheel. As herein shown, said

2
rim is made of I-beam cross-section and the sprocket chain rests in the groove between the lateral flanges thereof and engages suitable teeth 54 thereon, as shown in Fig. 16. The said wheel embraces in its construction a central hub 55 and spokes 56 extending therefrom to the rim 53. The hub of said wheel is mounted on an axle 57 that is supported at its ends in bearing boxes 58 mounted upon the rear ends of the arms 40, as shown in Fig. 2.

10 Plow bearing arms 60, 60, herein shown as six in number, are arranged alternately on opposite sides of the wheel and are each located in advance of one of the scoops, relatively to the direction of rotation of the wheel. Said plow bearing arms extend radially beyond the rim and carry at their outer ends cutters or plows 61 shown as made of the same general form as are the plows of my aforesaid prior patent. Said plow bearing arms are arranged at varying distances from the wheels so that the plows carried thereby, which are narrower than the ditch bottom, may cover the entire bottom of the ditch. All but one or two of the plow bearing arms are fixed stationary. The other plow bearing arms may be pivoted at their inner ends to one of the spokes 56 of the wheel by means of pivot pins 62 (Fig. 16), whereby such pivoted arms may swing laterally on the ascending side of the wheel to prevent the plows carried thereby from clashing with the wheel driving chain 52. Braces 63 strengthen the connection of the plow bearing arms with the wheel. The scoops, as herein shown, are metallic vessels or buckets having bottom, inner, outer and side walls. The advance edges of the outer walls are sharpened and act as cutting edges in advance movement of the scoops. Said scoops operate both to cut their way through the material to be excavated and also to scoop up material previously loosened by the plows. Eight scoops are herein shown arranged alternately at the sides of said wheel rim vertically beyond the periphery thereof. If the excavation to be dug is wider than the scoops, the said scoops will stand in overlapped relation to each other circumferentially of the wheel. If the excavation is the same width as the scoops they will be located circumferentially in alignment with each other. In order that they may stand in overlapped relation as stated, it will obviously be necessary that some of the scoops be located laterally a distance away from the wheel greater than others of the scoops. In order to obtain these results I may provide adjustable stops for limiting the inward movement of the scoops in the same general manner shown and described in my aforesaid prior patent.

50 The scoops 51 are carried by the outer ends of the scoop bearing arms, each of which consists of two members 75, 76 that are spaced a distance apart at their inner ends and converge toward their outer ends and are connected at their outer ends by webs or plates 77. The said members of the scoop bearing arms are hinged to certain of the spokes 56 of the wheel, such spokes being provided with lugs 78, 78 and the inner ends of the arm members being provided with correspondingly hinged lugs 79, 79 (Fig. 3). The members 76 of said arms are made longer than the members 75 and are hinged to said spokes near the hub of the wheel, while the shorter members 75 are hinged to said spokes between the hub and the rim of the wheel. Inasmuch as the said arm members are hinged to the spokes at different radial

distances from the center of the wheel, it follows that, as the wheel rotates towards the breast of the excavation, the scoops at the ascending side of the wheel have a tendency to swing laterally therefrom when the supporting arms thereof reach a horizontal position. In 70 the continued rotation of the wheel with said scoops in their extended positions, said scoops are caused to be inverted with the effect of dumping or depositing their contents alongside the ditch or excavation. When a spoke to which a given scoop arm is pivoted passes its 75 vertical position, the said scoop swings inwardly towards the rim of the wheel; the operation of the scoop arms in this respect being generally the same as disclosed in my prior patent before referred to. Means are provided for locking said arms to the outer part or 80 rim of the wheel in such manner as to prevent the backward stress on the arms from exerting undue or excessive stress on the pivots of said arms. A practical form of locking device for this purpose is shown in Fig. 3 and Figs. 11 to 15, inclusive, and is made as follows: 85

The longer member 76 of each arm is provided with a loop or bail 85 that extends forwardly therefrom, relatively to the operative direction or rotation of the wheel, and is adapted to be brought laterally against the rim of the wheel or a stop on said arm when the arm is in its 90 retracted position. 86 designates a latch that is pivoted at the inner side of the rim and is provided with a hook or detent 87 adapted to engage the loop or bail 85 of the scoop arm when the latter is swung inwardly. As herein shown, said latch is forked at its rear end and 95 the arms of the forks are pivoted by means of suitable pins 88 to the flanges of the I-beam shaped rim. The latch is so formed that the hook or detent fits outside of the rim flange on the side thereof adjacent to its associated scoop arm. The said latch 86 is held normally 100 pressed toward the rim by light springs 89 attached to the rim and to said latch (Figs. 11 and 12). The end of the latch just inside of its hook rests in engagement with the lateral arm 90 of a short lever 91 which is pivoted to the web portion of the I-beam rim to swing in a 105 plane transverse to that of the latch. Said arm 90 extends laterally over the flange of the rim and is provided with an outwardly turned lug 92 that is parallel with said flange. Said lever 91 is held, by means of a spring 93, normally towards the side of the rim adjacent its 110 associated scoop arm with the lug 92 spaced a distance from the rim (Figs. 11 and 13). It will thus be seen that the arm 90 holds the hooked end of the latch radially inside of the loop or bail of the scoop arm so that when the scoop arm is retracted inwardly, the loop or 115 bail thereof strikes the lug 92 and pushes the same and the latch supporting arm inwardly until said arm is moved out of the path of the swinging latch, whereupon said latch slips off the arm 90 and is forced into engagement with the loop or bail 85 in a manner to lock the 120 scoop arm to the rim for the purpose stated. The latch thus arranged serves to hold the scoop arm firmly interlocked with the outer or peripheral part of the wheel while the scoop is being forced in cutting action against the breast of the excavation.

125 Means are provided for releasing the locking devices at points in the rotation of the wheel when the scoops have been moved out of cutting contact with the breast of the excavation in order to permit the scoops and their arms to swing laterally outwardly in a manner to 130

dump the contents of the scoops. Such release is effected in the present instance by means set in operation by the lateral swinging movement of the scoop arm next in advance thereof, the arrangement being as follows: A chain or cable 100 is attached at one end to the latch 86 of each locking device (Figs. 3, 11 and 12) and is attached at its other end to that one of the spokes 56 next in advance of said scoop arm or other stationary part of the wheel. 101 designates a short chain or cable 10 attached at one end to the chain 100 midway of its length and at its other end to one of the members of the scoop bearing arm next in advance of the scoop with which the latch in question is associated. This arrangement of the parts is such that the swinging of each scoop bearing arm laterally away from the wheel to its dumping position effects the release of the lock of the scoop bearing arm next in rear thereof, and which is just being moved out of its cutting or operating position, whereby the said latter scoop and its arm are free to swing laterally from the wheel when it, in turn, reaches a horizontal or substantially horizontal position. After each scoop is thus swung outwardly and is dumped by reason of the inversion of the scoop, said scoop and its arm are retracted inwardly towards the wheel and are again 25 locked to the wheel rim by the locking device described.

As before stated, means are provided for swinging one of more of the plow bearing arms laterally away from the wheel on the ascending side thereof so as to prevent the plow or plows carried thereby from clashing with the wheel driving chain 52. A convenient mechanism for effecting this result is shown in Figs. 3, 15 and 16 and is made as follows: 104 designates a bell crank lever which is pivoted to a bracket 105 fixed to the lateral side of the wheel rim. The longer arm 106 of said bell crank lever extends parallel with the plow bearing arm, while the shorter arm thereof extends transversely across the lateral face of said arm when the arm is in its innermost or retracted position. Said longer arm of the bell crank lever engages a pin or stud 108 extending laterally from the plow bearing arm. The shorter arm of the lever is provided with a lug 109 to which is attached a chain 110 by which the lever is swung on its pivot in a manner to swing the longer arm of the same toward said pin or stud 108 and thereby 45 force the plow bearing arm laterally away from the wheel rim. The said bell crank lever is held in the position shown in Fig. 16 by means of a spiral spring 111 attached at one end to the short end of said lever and at its other end to the plow bearing arm. A stop 112 formed on a flat plate 113, attached to and extending laterally from the plow bearing arm, serves to limit the swing of said lever under the action of the spring 111. The said bell crank lever is swung on its pivot to throw the scoop bearing arm laterally from the wheel frame 55 by means operated by the scoop bearing arm second in advance thereof relatively to the direction of rotation of the wheel. The construction herein shown for effecting this result is made as follows: The said chain 110, which is attached at one end to said bell crank lever, 60 is attached at its other end to a spoke 56 second in advance of said lever.

114 designates a short chain which is attached at one end to the chain 110 midway of its length and at its other end to the scoop bearing arm second in advance of 65 the plow bearing arm associated with the bell crank

lever referred to, and located on the side of the wheel opposite to the last mentioned scoop bearing arm. Thus it will be seen that as a scoop bearing arm, thus associated with a plow bearing arm, swings laterally outward away from the wheel frame, it acts, through the 70 medium of the chains 114 and 110, to operate the bell crank lever 104 associated with the plow bearing arm and thereby swings the said plow bearing arm laterally from the wheel a distance to clear it from the operating chain 52 as the plow rises on the ascending side of the 75 wheel. The plow bearing arm is thus held outwardly until the scoop bearing arm which controls its movement is retracted by gravity inwardly to the wheel. The short arm of the bell crank lever 104 engages the plate 113 in such manner as to constitute a stop to normally 80 prevent the plow bearing arm swinging away from the wheel, as shown in Figs. 16 and 17.

As a further and separate improvement, I have provided a plurality of side cutters for cutting or trimming the side walls of the ditch excavation. As herein shown, two of such side cutters are employed, one located at one lateral side of the wheel and the other at the other lateral side thereof. 115, 115 (Fig. 3) designate said side cutters which consist of elongated flat blades. They are attached to or extend radially outwardly from the long arm 115^a of a bell crank lever 116, which lever is pivoted at its angle to the rim 53 of the wheel frame to swing laterally from the plane of the wheel. The ends of the arms of said bell crank lever are connected by an oblique brace or strut 117. The outer ends of said cutters are curved laterally, as shown at 118. The said cutters are braced from the wheel rim by oblique braces 119, 119 attached at their outer ends to the cutter blades and pivoted at their inner ends to the wheel rim, as shown in Fig. 3. The mechanism 90 for swinging said cutter arm levers on their pivots to swing the side cutters towards and from the plane of the wheel is made as follows: 120 designates an eccentric 95 fixed to the stationary wheel bearing axle. Said eccentric is surrounded by an eccentric strap 121 provided with lugs 122, 122 (Figs. 18 and 19). 123, 123 designate reciprocating eccentric bars which are attached at their inner ends to said lugs, one of which is rigidly attached to its lug and the other of which is pivoted thereto. The outer ends of said eccentric bars have guiding engagement in loops 123^a, 123^a formed on bars 124 suitably 100 fixed in the wheel frame (Figs. 3 and 20).

125, 125 designate swinging bars, each of which is hinged at one end to an adjacent spoke 56 and is pivoted between its ends at 126 to the associated eccentric 115 bar. Each of said swinging bars 125 extends beyond its eccentric bar and is loosely connected with the short arm of the adjacent bell crank lever 116 by a link 127.

The relation of the eccentric 120 with respect to the wheel frame and to the side cutters 115 is such that the 120 side cutters are swung outwardly into engagement with the side walls of the ditch or excavation at the bottom of the curved breast of the excavation and during the subsequent upward or forward movement of the side cutters they are swung gradually outwardly and reach their farthest divergence from the wheel at the time or just after they leave the ditch or excavation. As a result of this arrangement and operation of the side cutters, the side walls of the ditch, when finished, diverge 125 outwardly from the bottom to the top of the ditch. The 130

slanting of the walls of the ditch in this manner is often necessary by reason of the character of the earth formation in which the ditch is being excavated to prevent the walls of the ditch from caving inwardly and thereby rendering it unnecessary to brace the ditch walls. Again the walls may be thus slanted to avoid the caving in of the walls of an open ditch. It is obvious that said side cutters may be otherwise arranged on the wheel and may in the form shown or a modified form be applied to other types of wheel ditching machines than that herein shown.

As a further and separate improvement, the scoops are connected with the scoop arms in such manner that upon the occasion of unusual stress being thrown thereon, as for instance, when the scoops are brought into contact with an immovable obstruction, as a stone, located in the path of the scoops, said scoops will yield to avoid any of the parts, upon which stress is thus thrown, becoming broken or strained. Such yielding of the scoops may be effected by hinging the scoops to their arms and interposing a spring connection between the scoops and their arms, or interposing a break bar. The latter device is here shown. As herein shown, the scoops are hinged at the forward margins of their inner walls to the outer ends of the scoop arms, in the manner shown in Fig. 3, and breaking bars 127^b are interposed between the inner sides of said scoops and the scoop bearing arms. As shown, the ends of said breaking bars enter sockets 128 and 129 on the scoops and arms, respectively. Said breaking bars are made of wood and are loosely set in said sockets provided therefor. In order to hold the scoops in proper relation to the bars and scoop arms, chains 130 are provided, each of which is attached at one end to the rear side of a scoop and at its other end to the scoop arm near the inner end of the breaking bar.

Means are provided for limiting the lateral swing of the scoop bearing arms while they are passing through their dumping positions. This may be effected by limiting or stop chains attached in any suitable manner to the wheel frame and scoop arms. I have, however, provided a special form of limiting device, which is shown more clearly in Figs. 3 and 10, and is made as follows: It comprises a short arm 135 hinged to the inner side of the rim of the wheel at 136 and a short length of chain 137 attached at one end to the end of said arm and at its other end to the associated scoop bearing arm. Said arm is hinged to swing laterally towards and from the plane of the wheel and when in its innermost or retracted position, it is disposed radially with respect to said rim and generally parallel with the scoop-bearing arms. Said limiting arm is held in its innermost position by means of a spring 138 attached at one end to said arm and at its other end to an adjacent spoke 56. As shown, the limiting arm 135 is made of generally V-shape to provide two points of pivot but the form of the arm may be varied while producing the same result. In Fig. 10 said limiting device is shown in full lines in its inner or retracted position and in dotted lines in its outer or extended position.

The mechanism for propelling the machine is so constructed that when operating in the excavation the machine is advanced intermittently through a step-by-step movement, and is also capable of adjustment to propel the machine forwardly at a desired speed when

the machine is to be moved from place to place. The excavating wheel is driven forward continuously during the step-by-step movement of the wheel during the excavating operation.

Referring now to the driving mechanism for rotating the scoop bearing wheel, the parts are made as follows: 138 designates a chain or belt that is trained about a wheel on the crank-shaft 139 of the engine 34 and about a similar wheel 140 fixed to a horizontal shaft 142 extending transversely across the machine frame (Figs. 2 and 7) and hereinafter termed the main driving shaft. The said chain and wheels are of the sprocket type, as are all the belts and wheels of the driving mechanism, but this arrangement may be varied as desired. 143 designates a second wheel mounted on said shaft 142. Said latter wheel is mounted loosely on said shaft and is locked to the shaft at will by a clutch formed on the adjacent ends of the hubs of said wheels 140 and 143. In the present instance, the wheel 140 slides endwise of the shaft to bring the clutch members together. A clutch lever 146 is connected with the hub of said wheel 140 to move it towards and from the hub of the wheel 143. 147 designates a driving belt or chain that is trained about said wheel 143 and also about a sprocket wheel 148 fixed to a shaft 149 that is rotatively mounted at its ends in bearings 150, 150 carried by the vertical beam 43 of the auxiliary frame 42 (Figs. 3, 5 and 7). The laps of said driving chain 147 engage idlers 151, 152, the former of which is rotatively mounted on a horizontal shaft 153 extending between the traction wheels 27 and constituting the differential gear shaft of the driving mechanism, and the latter of which is mounted in a hanger 154 depending from the rear axle 29 of the main frame. Fixed to the shaft 149 is a second sprocket wheel 155 which is operatively connected by a driving belt or chain 156 with a sprocket wheel 157 that is fixed on a rotative shaft 158 located above the shaft 149 and rotatively mounted at its ends in bearings 159 carried by the vertical parallel beams 43 of the said auxiliary frame 42. Fixed to said shaft 158 is a smaller sprocket wheel 160 about which is trained the excavating wheel driving chain 52 before referred to. The excavating wheel is thus continuously driven from the engine through the connection described so long as the clutch device associated with the wheel 143 is in position to connect said wheel with the main shaft 142. It will, of course, be understood that said clutch is disconnected at times when the machine is driven from place to place by its own power.

Referring now to the mechanism for driving the machine forward in a step-by-step manner during the rotation of the excavating wheel, these parts are made as follows: Fixed to said main driving shaft 142 is a sprocket wheel 165 which is connected by a sprocket chain or belt 166 with a wheel 167 fixed to a short horizontal shaft 168 rotatively mounted in the main frame in rear of the main driving shaft. 169 designates a second short rotative shaft mounted in said main frame and in rear of the shaft 168. The shaft 169 is provided at its outer end at the side of the machine with a gear pinion 177 that meshes with the principal gear 178 of a differential gear mechanism, designated as a whole by 179, and mounted on the differential gear shaft 153. Said differential gear mechanism may

be made of any suitable type and is not herein fully illustrated. The two parts of said shaft 153 at each side of the differential gear mechanism are provided at their ends with pinions 180 which mesh with gear wheels 181 fixed to the traction wheels 27 of the main frame and through which driving power is transmitted to said traction wheels. Non-rotatively fixed to the shaft 169 is a ratchet wheel 185 (Figs. 1, 2 and 8). The teeth of said ratchet wheel are engaged by a gravity 5 pawl 186 carried by a vertically swinging arm 187 that is swingingly mounted on the shaft 169. Non-rotatively fixed to the companion shaft 168 is an eccentric disk 188 surrounded by an eccentric strap 189. 190 designates a reciprocating eccentric bar or link that is 10 connected at one end to said strap and at its other end to said swinging pawl carrying arm 187. 191 designates a holding detent that is pivoted to a cross-bar 192 of the main frame and engages the teeth of said ratchet wheel in a manner to hold said wheel from backward 15 rotation.

The operation of the step-by-step advancing mechanism described is as follows: The shaft 168 is rotated continuously through its connection with the shaft 142 whereby is imparted to the eccentric 188 a like continuous rotation. In each rotation of said eccentric the pawl carrying arm 187 is swung forwardly and backwardly by reason of its connection with the eccentric through the link 190, and the pawl 186 carried thereby acts during each advance movement to rotate the 20 ratchet wheel forwardly one step, the shaft 169 partaking of a like rotation. Through the medium of the intermeshing gears 177 and 178, 180 and 181, such rotation of the shaft 169 is communicated in a step-by-step manner to the traction wheels, whereby the machine is advanced intermittently.

Referring now to the mechanism for driving the machine from place to place under its own power, with the excavating wheel out of action, the parts which co-operate to this end with the driving mechanism already described, are made as follows: Mounted on said second shaft 169 is a sprocket wheel 170 the hub of which is loose on said shaft permitting the shaft to rotate therein. The said sprocket wheel 170 is operatively connected, through the medium of a driving belt or chain 171, with a small sprocket wheel 172 on the main shaft 142, whereby the shaft 169 is rotated from said main shaft 142. Said shaft 169 may also be driven from the shaft 142 by a like sprocket chain or belt trained about pulleys 173 and 174 on said main shaft and the hub of the sprocket wheel 50 170, respectively. Said sprocket wheels 173 and 174, respectively, and the speed of the machine when traveling from place to place may be varied by changing the driving belt or chain 171 from one set to the other. The hub is adapted to be locked to the shaft 169 by means of 55 a clutch, the members of which are formed partially on said hub and partially on a collar 175 which is nonrotative or but slides longitudinally of said shaft. Said clutch collar is operated by means of a lever 176.

When the machine is to be moved from place to place, 60 the main shaft 142 is disconnected from the shaft 168 by removing the chain or belt 166 and driving power is communicated from the shaft 142 through the belt 171 to the gear wheel 170 or 174, as the case may be. At this time said gear wheels 170 and 174 are locked to the

shaft 169 through the medium of the clutch collar 175 65 before referred to. Power is transmitted from the shaft thus connected with the engine through the gear wheel 177, the differential gear and the pinion 180 to the gear wheels 181 of the traction wheels in the same manner as when driving power is transmitted intermittently to 70 the traction wheels, with the exception that the power is transmitted continuously instead of a step-by-step manner. When the machine is to be moved some distance from one place of operation to another, the driving chain 171 is trained over the gears 173 and 174 on the 75 shafts 142 and 189, respectively, thereby providing a high speed gear for driving the machine. It will, of course, be understood that when the machine is thus driven from place to place, the sprocket wheel 143 is disconnected from the driving shaft by means of the 80 clutch lever 146 before described. It is necessary, when moving the machine from place to place, to elevate the scoop bearing or excavating wheel 60 above the general level of the roadway. This is effected through the medium of the pivotal wheel bearing frame comprising the arms 40 and the rigidly connected beams 41, 85 before referred to, together with the following mechanism now to be described co-operating therewith.

200 designates a drum mounted on a horizontal shaft 201 extending transversely across the main frame in 90 front of and parallel with the main driving shaft 142. 202 designates a cable, one end of which is fixed to said drum and the other end of which is fixed to the frame 26 adjacent to the drum. In the bight of said cable and near the level of the upper ends of the beams 41, is located a pulley 203 (Fig. 1). 204 designates a chain or cable that is attached at one end to said pulley, is trained between its ends over a guide pulley 205 (Figs. 1 and 4) suspended from the upper ends of the beams 41, and is connected at its other end with the upper end of 100 an inverted V-shaped frame 206, the lower diverging ends of the members of which frame are pivotally connected at 207 (Fig. 4) with the auxiliary, vertically sliding frame 42. The connection of said chain with said inverted V-shaped frame is so close to the pulley 205 105 that when one end of the cable is wound on the drum it acts to pull the vertical portion of the wheel supporting frame forwardly or towards the drum and, by reason of the pivotal connection of said frame with the main frame 25, the rearwardly directed wheel bearing arms 110 40 of said frame may be raised. In this manner the wheel may be raised above the level of the ground or may be vertically adjusted to excavate ditches of different depths as desired. A convenient means of rotating said drum to effect the operation of raising and lowering 115 the wheel consists in providing the drum shaft 201 with a worm wheel 210 which is engaged by a worm 211 on or carried by an oblique shaft 212 that is mounted in a suitable bearing 213 on the main frame of the machine. Said shaft is provided with a hand wheel 214 by which 120 it may be turned to rotate the said drum. Provisions are also made for raising said excavating wheel above the level of the ground by the power of the engine. The mechanism for this purpose comprises beveled gear wheel 215 on the end of the main driving shaft 142 (Figs. 125 1 and 2) and a conical pinion 216 carried by the end of said worm screw-shaft 212. The said wheel is movable endwise on the shaft 142 and is adapted to be moved in-

wardly into engagement with said conical gear by means of a lever 217 that is pivoted to the main or carrying frame and engages at its end the outer face of said bevel wheel 215. When said gears are brought into mesh in this manner it will be obvious that the rotation of the main driving shaft 142 communicates rotative movement to the screw shaft with the result of winding the cable 202 on the drum and raising the wheel as described.

- 10 Referring now to the sliding connection of the auxiliary frame 42 with respect to the upright members 43 of the wheel supporting frame and its coöperation with the cable 202, it will be noted that the purpose of said sliding auxiliary frame and the parts which coöperate therewith, is to enable the scoops carried by the wheel to loosen and raise obstructions, such as stones, against which the scoops are forced and also to permit the excavating wheel to be automatically raised upon such occasion if the obstruction be too large or heavy to be thus loosened. The operation of this feature of the construction will be made clear from a consideration of the following: In case one of the plows or scoops strikes such obstruction an extraordinary stress is brought on the lever lap of the driving chain 52 which tends to draw the upper end of the auxiliary frame and the vertical members 41 of the wheel supporting frame towards the excavating wheel. Such tendency is resisted, however, by means of the inextensibility of the cable 202 and chain 204. The result of such extraordinary stress on the lower lap of said driving chain 52 is to effect a downward shifting of the auxiliary frame in its bearings. Such downward shifting of the auxiliary frame in this manner is resisted by the immovability of the pulley 203. The pulley 205, over which the chain 204 is trained, is located in front of the pivot of the wheel supporting frame and the tension brought on said chain 204 serves to swing the upright members 41 of said wheel supporting frame forwardly about its pivot, with the result of tending to swing the rearwardly directed arms 40 and the excavating wheel upwardly. Such tendency to swing the wheel upwardly has the effect of exerting an upward and forward pull on the obstruction, as a stone, which will dislodge such obstruction so that it may be removed from the excavation by the scoops if in fact such obstruction be of such size as to admit of its dislodgment and removal. If the obstruction cannot be thus dislodged and removed the upward swinging of the rear end of the wheel carrying frame disengages the scoop or plow from the obstruction thus avoiding an undue stress being thrown on the machine.

It will be understood that many of the details described herein may be varied within the spirit of the invention and that much of the construction is applicable to types of ditching machines different from that herein shown. I do not wish to be limited to such details except as hereinafter made the subject of specific claims.

I claim as my invention:—

- 60 1. An excavating machine embracing a rotative wheel, scoop bearing arms hinged to the wheel and having lateral movement relatively thereto, scoops carried by said arms, locking devices for locking the scoops inwardly against the wheel to hold them from backward movement relatively

to the direction of rotation of the wheel, and means for releasing the locking devices, each comprising a chain attached at one end of the locking device and at its other end to a stationary part of the wheel, and a chain attached at one end to an intermediate part of the first chain and at its other end to the arm of the scoop in advance of the scoop with which said locking device is associated.

2. An excavating machine embracing a rotative wheel, scoop bearing arms hinged to the wheel and having lateral movement relatively thereto, scoops carried by said arms, and locking devices for locking the scoops inwardly against the wheel, each comprising a loop on the scoop arm, a radially swinging latch pivoted to the wheel rim and provided with a hooked end adapted to engage said loop, and means for automatically engaging said hooked end of the latch with the said loop when the scoop arm is swung inwardly.

3. An excavating machine embracing a rotative wheel, scoop bearing arms hinged to the wheel and having lateral movement relatively thereto, scoops carried by said arms, and locking devices for locking the scoops inwardly against the wheel, said locking devices each embracing a loop on the scoop arm, a radially swinging latch pivoted to the wheel rim and provided with a hook adapted to engage said loop, and a device for normally holding the hooked end of the latch out of the path of the loop constructed to be moved inwardly towards the wheel rim when said arm is swung inwardly to permit the hooked end of the latch to swing into engagement with said loop.

4. An excavating machine embracing a rotative wheel, scoop bearing arms hinged to the wheel and having lateral movement relatively thereto, scoops carried by said arms, and locking devices for locking the scoops inwardly against the wheel, said locking devices each embracing a loop on the scoop arm, a radially swinging latch pivoted to the wheel rim and provided with a hook adapted to engage said loop, a lever pivoted to said rim to swing in a plane transverse to the plane of movement of the latch and provided with an arm which normally holds the hook of said latch out of the path of said loop, said loop engaging the arm to shift the same inwardly out of the path of the hooked end of the latch to permit the said hooked end of the latch to swing into engagement with said loop.

5. An excavating machine embracing a rotative wheel, scoop bearing arms hinged to the wheel and having lateral movement relatively thereto, scoops carried by said arms, and locking devices for locking the scoops inwardly against the wheel, each comprising a loop on the scoop arm, a radially swinging latch pivoted to the wheel rim and provided with a hooked end adapted to engage said loop, means automatically engaging said hooked end of the latch with the loop when the arm is swung inwardly, and means operated by the movement of each scoop arm to release the latch belonging to another scoop arm.

6. An excavating machine comprising a rotative wheel and a chain for driving the wheel, scoops carried by the wheel, plow bearing arms, one or more of which are hinged to the wheel to swing laterally toward and from the plane of the wheel and plows carried by said arms.

7. An excavating machine comprising a rotative wheel, a chain for driving said wheel, scoops carried by the wheel, plow bearing arms, one or more of which is hinged to the wheel to swing laterally toward and from the plane of the wheel, plows carried by the said arms, and means for normally holding the hinged plow bearing arms in their retracted position toward the rim of the wheel.

8. An excavating machine comprising a rotative wheel, a driving chain for rotating said wheel, scoops carried by the wheel and movable laterally toward and from the plane of the wheel, plow bearing arms, one or more of which are pivoted to the wheel to swing toward and from the plane of the wheel, plows carried by said arms, and means operated by the outward movement of a scoop for swinging a plow bearing arm laterally away from the plane of the wheel to clear the plow thereof from said driving chain.

9. An excavating machine embracing a rotative wheel, a chain for driving the same, scoops carried by the wheel,

- plow bearing arms, one or more of which is pivoted to the wheel to swing laterally therefrom, and means for swinging a movable plow bearing arm laterally away from the plane of the wheel, comprising a bell-crank lever pivoted to the wheel to swing laterally therefrom, and means for swinging said bell crank levers on their pivots. 80
10. An excavating machine embracing a rotative wheel, a driving chain for rotating said wheel, scoop bearing arms hinged to the wheel and having lateral movement relative thereto, scoops carried by said arms, plow bearing arms, one or more of which is hinged to the wheel to swing laterally toward and from the plane of the wheel, plows carried by the latter arms, and means for swinging a plow bearing arm laterally from the plane of the wheel on the 15 rising side of the wheel to clear the plow carried thereby from said wheel driving chain, comprising a bell crank lever pivoted to the wheel and adapted to be swung laterally from the plane thereof, a co-acting part on said plow bearing arm engaged by said bell-crank lever, and 20 means cooperating with said bell crank lever for normally holding the plow bearing arm inwardly against said wheel.
11. An excavating machine embracing a rotative wheel, scoops carried by the wheel, and side cutters also carried by said wheel to slant the side walls of the excavation 25 from the bottom thereof outwardly, for the purpose set forth.
12. An excavating machine embracing a rotative wheel, scoops carried by the wheel, side cutters extending radially from and pivoted to the wheel to swing laterally, and 30 means for operating said side cutters, for the purpose set forth.
13. An excavating machine embracing a rotative wheel, scoops carried by the wheel, and side cutters extending radially from the wheel and hinged to swing laterally therefrom, said side cutters being provided with inwardly turned ends. 35
14. An excavating machine embracing a rotative wheel, scoops carried by the wheel, side cutters extending radially from the wheel and hinged to swing laterally therefrom, 40 and an eccentric for actuating said side cutters.
15. An excavating machine embracing a rotative wheel, scoops carried by the wheel, side cutters extending radially from the wheel and hinged to swing laterally therefrom, and means for actuating said cutters comprising a stationary eccentric arranged axially of the wheel, and 45 operative connections between said eccentric and said side cutters.
16. An excavating machine embracing a rotative wheel, scoops carried by said wheel, side cutters extending radially from said wheel, bell crank levers pivoted to the wheel rim to swing laterally from the plane of the wheel, a stationary eccentric located axially of the wheel, an eccentric strap surrounding said eccentric and bars connected at their inner ends with said strap and operatively connected at their outer ends with said bell crank levers. 50
17. An excavating machine embracing a rotative wheel, scoop bearing arms carried thereby, scoops hinged to the outer ends of said arms, and means rigidly connecting the scoops with said arms, constructed to permit the scoops to 60 yield relatively to said arms when undue stress is placed thereon, for the purpose set forth.
18. An excavating machine embracing a rotative wheel, scoop bearing arms carried thereby, scoops hinged to the outer ends of said arms, and breaking bars interposed between said arms and scoops, for the purpose set forth. 65
19. An excavating machine embracing a rotative wheel, scoop bearing arms carried thereby, scoops hinged at their forward or cutting margins to said arms, and breaking bars interposed between said arms and said scoops near 70 the rear ends of the latter, for the purpose set forth.
20. An excavating machine embracing a rotative wheel, scoop bearing arms carried thereby, scoops hinged to said arms, breaking bars interposed between said arms and said scoops, and chains connecting said scoops with the arms, for the purpose set forth. 75
21. An excavating machine embracing a rotative wheel, scoop bearing arms hinged to said wheel to swing laterally towards and from the plane of the wheel, and devices 80 for limiting the outward swing of said arms, each embracing a bar hinged to the wheel and a chain or cable attached at one end to said bar and at its other end to a scoop bearing arm, as and for the purpose set forth. 85
22. An excavating machine embracing a rotative wheel, scoop bearing arms hinged to said wheel to swing laterally towards and from the plane of the wheel, and devices for limiting the outward swing of said arms, each comprising a bar hinged to the wheel rim and a chain attached at one end to the outer end of said bar and at its other end to a scoop bearing arm, said bar, when the arm is in its retracted position, being transversely disposed relatively to the rim of said wheel. 90
23. An excavating machine embracing a rotative wheel, scoop bearing arms hinged to said wheel to swing laterally towards and from the plane of the wheel, devices for limiting the outward swing of said arms, each comprising a bar hinged to the wheel rim, a chain attached at one end to the outer end of said bar and at its other end to a scoop bearing arm, said bar, when the arm is in its retracted position, being disposed transversely relatively to the rim of said wheel, and a spring for holding said bar in its 100 retracted position.
24. An excavating machine embracing a frame, traction and steering wheels therefor, an excavating wheel carried by said frame, a motor on the frame for rotating the excavating wheel, and driving connections between said motor and traction wheels arranged to effect a step-by-step rotation of said traction wheels. 105
25. An excavating machine embracing a frame, traction and steering wheels therefor, an excavating wheel carried by said frame, a motor on the frame for rotating the excavating wheel, and driving connections between the motor and traction wheels embracing a ratchet wheel, a detent for holding the ratchet wheel from retractive rotation, an oscillatory pawl engaging said ratchet wheel to advance the same step-by-step and operative connections between 110 said ratchet wheel and traction wheels.
26. An excavating machine embracing a frame, traction and steering wheels therefor, an excavating wheel carried by said frame, a motor on the frame for rotating the excavating wheel, driving connections between said motor and traction wheels arranged to effect a step-by-step rotation of said traction wheels, and a direct driving connection between said motor and traction wheels designed for operative connection with said traction wheels alternately with said step-by-step driving connections, for the purpose set 115 forth. 120
27. An excavating machine embracing a frame, traction and steering wheels therefor, an excavating wheel carried by said frame, a motor on the frame for rotating the excavating wheel, and driving connections between said motor and traction wheels embracing a gear on the traction wheel gears, a rotative shaft geared to said traction wheel gears, a ratchet wheel on said shaft, means driven by the motor for advancing said ratchet wheel step-by-step, a detent for holding the ratchet wheel from backward rotation, a gear normally loose on said shaft and adapted to be non-rotatively fixed thereto at will and means for driving said latter gear from the motor. 130
28. In an excavating machine, the combination with a wheeled frame, means for advancing the frame and an excavating wheel carried by the frame provided with excavating scoops, and a chain for driving the excavating wheel, of means operating when one of the scoops strikes an obstruction to exert an upward pull as well as a forward pull on the obstruction, for the purpose set forth. 140
29. An excavating machine embracing a wheeled frame, a wheel carrying frame pivoted thereto, an excavating wheel mounted on the latter frame, means for advancing the wheeled frame and for rotating the wheel, the latter driving connections embracing a driving belt trained about said excavating wheel, and means operated by stress on said drive belt, when the excavating wheel is retarded by an obstruction in its path, and independent of the tractive force exerted on the wheeled frame to raise said wheel, for the purpose set forth. 145
30. An excavating machine embracing a wheeled frame, 150
- 155

a wheel carrying frame pivoted thereto, an excavating wheel mounted on the latter frame, means for advancing said wheel frame and for rotating said wheel, the latter embracing a driving belt trained about said excavating wheel and a wheel rotated by the driving means, an auxiliary frame on which said latter wheel is mounted, said frame having sliding connection with the excavating wheel carrying frame, and a tension cable fixed to the wheeled frame and connected through the wheel carrying

frame with said auxiliary frame, for the purposes set forth.

In testimony, that I claim the foregoing as my invention I affix my signature in the presence of two witnesses, this 4th day of June A. D. 1907.
